UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

COMBINED FOLDER AND GUIDE FOR SEWING-MACHINES

1,317,865.

Specification of Letters Patent.

Patented Oct. 7, 1919

Application filed April 15, 1916. Serial No. 91296.

To all whom it may concern:

Be it known that I, ALBERT H. DE VOE, a citizen of the United States, residing at Westfield, in the county of Union and State 5 of New Jersey, have invented certain new and useful Improvements in Combined Fold-ers and Guides for Sewing-Machines, of which the following is a specification, refer- 10 ence being had therein to the accompanying drawings.

This invention relates to improvements in combined folders and guides for sewing machines and has for its object to improve the folding and guiding mechanism of U. S. Patent No. 684,990, of October 22, 1901, to Laubscher, and to this end there is herein employed an edge-folder, a band-guide, an interposed tape-guide, means for releasing the tension on the tape passing through the latter when, for any purpose, it is desired to manually draw tape from the supply and means for giving to the tape guide lateral movements relatively to the lines of seam formation.

25 Referring to the accompanying drawings, which form a part of the specification, Figure 1 is a view in front side elevation of a Singer sewing machine equipped with the present invention. Figs. 2 and 3 are plan.
30 1 and rear side elevations, respectively, of Fig. 1. Figs. 4, 5 and 6 views in perspective of the edge-folder, band-guide and tape-guide, respectively. Fig. 7 is a detail later to be referred to. Fig. 8 is a view in perspective of
35 a portion of the sewing machine cloth and throat or needle-plate, illustrating the manner in which they are cut away to form a seat for the band-guide. Fig. 9 is a view showing the tape as an inner ply with the body-
40 fabric and tape folded back to better illustrate the manner of inserting the tape. Fig. 10 is a view similar to Fig. 9 showing the tape as an inner ply and the several plies secured together as in the finished product.

45 The present invention is herein shown and will be described as applied to a Singer two-needle sewing machine, but as the application of the invention is not limited to any particular variety of sewing machine, only
50 such reference will be made to the well-known parts of the latter as is thought essential for an understanding of its application.

Referring to the figures, 1 represents the sewing machine bed or base from which rises the standard 2 carrying the bracket-arm 3

and 4 the cloth-plate. As is common to machines of the present variety the needle-bar 5 is actuated from a commonly employed rock-shaft (not shown) journaled in suitable bearings formed in the bracket arm and operatively connected by a suitable crank connection (not shown) with the lower main- or driving-shaft 6 provided with the hand- or band-wheel 7, the needles, as 8, coöperating with suitable loopers (not shown) in a manner common to machines for effecting two thread elastic stitch seams. 9 denotes the feed-dog of one form of commonly employed four-motion feeding-mechanism, the details of which are unimportant to the present invention, 10 the throat- or needle-plate secured upon the cloth-plate by screws, as 11, the depressed surface 12 of said throat-plate in connection with the depressed surface 13 of the cloth-plate forming a seat for the 75 band-guide.

Referring now to the folding and guiding elements and the means for effecting their coöperation to properly present the fabrics to the action of the cloth-feeding and stitch-forming mechanism, 14 denotes the band-guide bracket-plate secured upon the cloth-plate by screws, as 15, and to the underside of said bracket is adjustably secured by screws, as 16, a band-guide bracket 16' carrying the band-guide 17 seated upon the depressed surfaces 12, 13 and provided with the usual folding scrolls, as 18, and a tape-loop 19, the latter later to be referred to. Upon the bracket 14 is suitably secured a scroll-plate bracket comprising a base 20, standard 21 and inclined shelf or support 22 upon which is adjustably secured by screws, as 23, the scroll plate 24 provided with the edge folding scroll 25, and to the standard 21 is adjustably secured by screw 26 a tape tension releasing bracket 27 provided with tension releasing finger or element 28.

29 represents the tape-guide bracket pivoted by screw 30 passing through an opening 31 formed in the latter and through an elongated slot 32 formed in the plate 14 and like slot (not shown) formed in the bracket 16' and threaded in the opening 33 formed in the lug 34 of the tape-guide shifting link 35, the opposite end of the latter being connected by a crank-arm 36 with a rock-shaft 37 journaled in suitable bearings formed in the flange 38 of the cloth-plate and bearing 39 (shown in dotted lines only) suitably se- 110
100

cured to the under side of said cloth-plate, said rock-shaft having suitably secured to its opposite end an operating rock-lever 40 provided with a lug 41 having a suitable opening (not shown) through which the cloth-presser lifting-rod 42 loosely passes.

The upper end of the rod 42 is suitably linked to the presser lifting lever 43 pivoted on a stud-screw 44 and at its forward end co-
10 operating with the lug 45 carried by the cloth-presser bar 46 provided with the cloth-presser 47, to move the latter vertically in opposition to the resiliency of the springs 48 and 48' when the rod 42 is actuated
15 through the manual manipulation of a suitable foot- or knee-treadle (not shown) connected with the treadle-rod 49, which latter is connected with the rod 42 by the collar 50 suitably secured to the latter, the spring 50
20 48' acting upon the upper end of said presser-bar in a manner common to sewing machines generally.

51 represents a tape-guide carried by the tape-guide bracket 29 which, at its forward 25 end, is provided with a V-shaped notch 52 through which, by the employment of a suitable instrument as pliers, the delivery end of the guide may be slightly widened or narrowed to meet slight variations in the width 30 of the tape, said bracket being provided with an extended portion or arm 53 having a turned down portion or lip 54 acted on by a spring 55, suitably secured to the flange 38, in opposition to the spring-catch 56 suit-
35 ably secured upon the cloth-plate 4. 57 denotes a tape controller spring the front end of which, in practice, bears down upon the tape 58, its opposite end being provided with an angular portion 59 having an opening 60
40 and flange 61, a tension stud 61' secured in the bracket 29 and provided at its upper end with a tension-nut 62 passing through said opening, and onto said stud is mounted a tension-spring 63 which, through the adjust-
45 ment of the nut 62, effects the desired tension on the tape, the curved portion or finger piece 64 making convenient the raising of the tension-spring off the tape and moving it to substantially the position shown in dotted lines Fig. 6 to make more convenient the 50 threading of the tape into the guide.

In practice the free edge of the fabric 65 is positioned in the scroll guide 25 which forms the fold 66, the tape 58 herein represented by an elastic tape, is threaded into the tape-guide 51 by first passing it from the supply through the loop 19 fast on the fold guide, followed by passing the end of the fabric which is to form the band 67 from 60 the supply through the opening 68 and into the folding scrolls 18, each of said fabrics being passed through their respective guides a distance sufficient to meet the action of the feed-dog when the machine is put into operation.

To better accommodate the threading of the material comprising the band 67, the tape-guide 51 is first swung on the pivot screw 30 to a position corresponding substantially to the dotted line position of the 70 tape tension spring 57, the tape-guide being held against swinging movements by the spring 55 acting to hold the tape-guide extension 53 into contact with the vertical wall 69 of the spring 56, which latter is capable 75 of being depressed to release said tension.

Having set forth the details in construction, the following co-operation of the parts will be readily understood.

Supposing the fabrics to have been positioned in their respective guides and in position to be acted on by the stitch-forming and cloth-feeding mechanism, as pointed out, the operator through a suitable treadle (usually foot-treadle) puts the machine into 85 operation and at the same time by the manipulation of a second treadle (usually knee-treadle) moves, through the connections 35, 36, 37, 40, 42, 49 and 50, the tape-guide 51 to the left a distance sufficient to bring the 90 front end of the presser-lifting lever 43 in engagement with the lug 45 carried by the presser-bar 46, which adjustment positions the tape 58 to receive the line of stitching 70 for a distance sufficient to insure it against 95 displacement, such adjustment of the tape-guide causing the tension releasing element 28 to engage the under surface of the oval portion 71 of the tape-tension spring 57 and move its free end out of engagement 100 with the tape. After the desired length of tape has been secured the operator permits the springs 48 and 48' to return the tape-guide to its normal position or position to direct the tape between the lines of stitching, 105 as shown in Fig. 9, until nearly the completion of the stitching operation when like adjustments are given the tape-guide and its spring to again secure the tape as in the first instance.

It is to be understood that when, for any purpose, it is desired to lift the cloth-presser the operator gives to the tape-guide adjusting treadle sufficient movement to cause the free end of the presser-lifting lever 43 to 115 engage and raise the presser-bar lug 45 and that the springs 55 and 56 act as guides to direct the movements of the tape-guide in a line transverse to the lines of seam formation.

Having thus set forth the nature of the invention, what I claim herein is:—

1. In a sewing machine for guiding and folding superposed plies of fabric, the combination with a cloth-presser bar and means 125 for raising the latter, a scroll-guide, a band-guide and an adjustably secured tape-guide, of means for effecting said adjustments including a tape-guide shifting link operatively connected with the means for raising 130

said cloth-presser bar, to give to said tape-guide movements in directions transversely of the lines of seam-formation.

2. In a combined folder and guide for 5 sewing machines, the combination of a stationary scroll-guide, a stationary band-guide, an adjustably secured tape-guide provided with a tape-tensioning spring adjustable with and independently of said tape-guide, and means for effecting said adjustments including a manually controlled shifting link pivotally connected at one end with 10 said tape-guide to give to the latter movements in directions transverse to the lines of seam formation.

15 3. In a combined folder and guide for sewing machines, the combination of a stationary scroll-guide, a stationary band-

guide, an adjustably secured tape-guide provided with a tape-tensioning spring adjustable with the latter, and independently of said tape-guide to release its tension on the tape, and means for effecting said adjustments including a manually controlled shifting link pivotally connected at one end with 20 said tape-guide to give to the latter movements in directions transverse to the lines of seam formation, and means including a tape-tension spring releasing element brought into effective relationship with said 25 tension spring by the lateral movements of said tape-guide.

In testimony whereof I have signed my name to this specification.

ALBERT H. DE VOE.
